(57) **CLAIM**

The ornamental design for a polishing pad, as shown and described.

DESCRIPTION

FIG. 1 is a perspective view of the polishing pad in accordance with the present invention in which only a portion of the surface appearance is illustrated, it being understood that the surface appearance covers the entire indicated surface, with an enlarged portion exploded out therefrom;

FIG. 2 is a workpiece-facing plan view of the polishing pad shown in FIG. 1 in which only a portion of the surface appearance is illustrated, it being understood that the surface appearance covers the entire indicated surface, with an enlarged portion exploded out therefrom;

FIG. 3 is an opposite plan view from that of FIG. 2 of the polishing pad shown in FIG. 1; and,

FIG. 4 is a side elevation view of the polishing pad shown in FIG. 1.

The broken lines form no part of the claimed design. The pattern designations shown in the figures are not intended to claim the specific patterns or materials but are instead intended to claim that the appearance of the outer ring (e.g., FIGS. 1 and 2) is different than the appearance of the backside of the pad (e.g., FIG. 3).

1 Claim, 2 Drawing Sheets
